No. 791,419.

PATENTED MAY 30, 1905.

F. A. HAWK.

COMBINED VEHICLE BRAKE SHOE AND STEP CONNECTION.

APPLICATION FILED DEC. 1, 1904.

UNITED STATES PATENT OFFICE.

FRANKLIN A. HAWK, OF CENTRALPOINT, OREGON.

COMBINED VEHICLE BRAKE-SHOE AND STEP CONNECTION.

SPECIFICATION forming part of Letters Patent No. 791,419, dated May 30, 1905.

Application filed December 1, 1904. Serial No. 235,076.

To all whom it may concern:

Be it known that I, FRANKLIN A. HAWK, residing at Centralpoint, in the county of Jackson and State of Oregon, have invented a new and Improved Combined Vehicle Brake-Shoe and Step Connection, of which the following is a specification.

This invention relates to improvements in that class of brake-shoe or block connections for wagons and carriages in which a single clamping-bolt is used for adjustably securing the block-holding clip or bars to the slotted end of the brake-bar; and it comprehends an improved arrangement of such fastening means and special construction of step, whereby the step can be quickly and firmly secured to the outer end of the brake-bar by the same means that secures the block or shoe.

In its more subordinate features my invention embodies certain details of construction which includes a special arrangement of that portion of the step-hanger which engages and clamps the brake-bar, whereby to prevent the said clamping portion from twisting or moving from the proper pendent position when the step-hanger is adjusted outwardly to the extreme position necessary in cases of a badly-dished wheel, all of which will be hereinafter fully explained, pointed out in the appended claims, and illustrated in the accompanying drawings, in which—

Figure 1 is a perspective view of as much of a vehicle necessary to illustrate the practical application of my invention. Fig. 2 is a perspective view of that end of the brake means to which the step is connected. Fig. 3 is a face view of such parts, the step and its clamping or hanger portion being shown to its extreme outer position in dotted lines. Fig. 4 is a transverse section thereof on the line 4 4 of Fig. 3. Fig. 5 is an end view of the same, showing the position the step and brake-bars assume when mounting the step. Fig. 6 is a detail perspective view of the several parts embodied in my invention separated.

The bar B, which may be of the conventional shape and mounted on the vehicle-

gear in the usual manner, has its opposite 50 flattened ends formed with elongated slots b b for the passage of the clamping-bolts C therethrough.

D D designate the brake-block or shoe-clip or members, each of which has its flanges 55 d d converging downwardly whereby to form dovetailed sockets to receive the shoe or block members E, as shown, and the back of the clips D have outwardly-projecting flanges d' d' at the upper and lower edges, 60 between which the ends of the brake-bar fit and which serve to hold the clips on the said bar ends in their proper horizontal position. The clip-bolt C has its head c countersunk on the inner face of the clip D and has its threaded shank in my construction extended sufficient to pass through the slotted brake-bar end and to receive the clip or clamping head of the step-hanger F, the peculiar construction of which and its co-operative connection 65 with the brake-bar and the shoe-clip forms the essential feature of this invention.

The head f of the hanger F has a central aperture f' for the bolt-shank c', and it has flanges f² f³ adapted to lap over the upper and 75 lower edges of the slotted end of the brake-beam, as shown in Fig. 4, and at the lower end the hanger F has an integral step member f⁴, which projects forwardly, as shown, but, if desired, may project outwardly.

By arranging these several parts and combining them in the manner shown and described the single nut G, applied to the end of the bolt-shank, serves to rigidly hold the shoe-clip and the step in the desired position, and 85 while positively holding the block or shoe from turning over upon the bar it likewise secures the step in its adjusted position, and by reason of connecting the step to the brake-clip bolt, as shown, the said step can be 90 shifted with the shoe-clip to suit the wheels and the necessity of separately adjusting the two parts, the clip and the step, is thereby avoided.

Another advantage in joining the step to 95 the brake-beam end in the manner shown is that in mounting the step the bar will be sufficiently rocked to apply the shoe against

the wheel, which not only braces the step and relieves the brake-gear of undue strain, but also applies the brake against the wheel.

The bolts C have squared portions next to their countersunk heads sufficient to extend through the squared portion of the apertures in the clips and into the slots in the brake-bar ends, whereby to absolutely prevent the turning of the said bolts when the bolt-nuts are being tightened or loosened.

Another and important advantage of my construction of brake devices is that the clamps being dovetailed permits of lost, worn, or broken shoes being renewed under very unfavorable circumstances, since no bolting of the shoe-blocks is required.

Having thus described my invention, I claim and desire to secure by Letters Patent—

1. A brake-bar, a brake-shoe clip adjustably mounted on the outer end of the brake-bar, a step pendently supported on the said outer end of the brake-bar, and a means for clamping the clip and the step member to the brake-bar, adapted to permit of the ad-

justment of the clip and the step with respect to the said brake-bar, in unison.

2. A brake-bar, a brake-shoe clip, a step pendently supported on the outer end of the brake-bar, a single clamping-bolt and nut device passing through the step, the brake-bar and the brake-shoe clip for securing the shoe-clip to the step, said brake-shoe clip and said step including means for engaging the brake-bar to prevent turning of the brake-shoe clip and the step on the bolt, substantially as shown and described.

3. In a brake mechanism of the character described, the combination with a slotted brake-bar end, the shoe-clip, and the bolt secured to the clip and projected through the slot in the brake-bar; of the step member having a clamping-head provided with flanges to project over the upper and lower edges of the brake-bar and apertured to receive the shank, and the clamping-nut.

FRANKLIN A. HAWK.
